CHAIR

Leandre A. Poisson, 215 Willoughby Ave.,
Brooklyn, N.Y.

Filed Apr. 25, 1963, Ser. No. 74,613

Term of patent 14 years

(Cl. D15—1)

FIG. 1 is a front perspective view of a chair in accordance with my new design;

FIG. 2 is a rear perspective view thereof;
FIG. 3 is a front elevation thereof; and

FIG. 4 is an end view thereof.

I claim:

The ornamental design for a chair, substantially as shown.
